UNITED STATES PATENT OFFICE.

GEORGE W. SLEEPER, OF WESTBOROUGH, MASSACHUSETTS, ASSIGNOR OF
ONE-HALF TO WILLIAM A. REED, OF SAME PLACE.

SHOE-UPPER-SPLITTING MACHINE.

SPECIFICATION forming part of Letters Patent No. 350,084, dated September 28, 1886.

Application filed November 9, 1885. Serial No. 182,256. (No model.)

To all whom it may concern:

Be it known that I, GEORGE W. SLEEPER, of Westborough, in the county of Worcester and State of Massachusetts, have invented a 5 new and useful Improvement in Manufacture of Shoes; and I do hereby declare that the following is a full, clear, and exact description of the same.

My invention is an improvement upon the 10 machine shown in Letters Patent of the United States granted to myself and William A. Reed, assignee, on the 16th day of June, 1885, and numbered 320,407.

The main purpose of my present invention 15 is to improve the form of leather upper as produced by the splitting-machine in respect to the parts severed along the line of the open front of the upper.

In the machine shown in the patent cited 20 above, the rollers feeding the blank to the splitting-knife were formed with cut-away portions with marginal walls serving as guides for the knife, so that the upper produced (as shown in my patent of the same date, No. 320,406) 25 had somewhat of an abrupt margin between the thick or unsplit and thin or split portions of the upper. In making shoes out of these uppers this margin or raised edge was necessarily shaved down to give the upper in these 30 parts a smooth and finished appearance.

In the machine hereinafter described the cylindrical rolls are used for feeding only, and the knife is caused to turn out of the leather by its own movement along lines approximating the edges of the front or margins of the uppers at the front opening, so that the upper part of the leather is severed from the lower on an incline plane from edge to edge, which leaves the sides of the upper smooth and without the abrupt shoulder, which required shaving off the sides, and consequently additional handling of the blank or upper after it had been split.

In my improved machine all the leather necessary to be removed from the sides of the upper is left upon the forward edges of the upper after it is split, and can be removed therefrom without additional labor when those edges are trimmed.

50 Besides attaining the object above described

I have improved the construction of the machine and increased its efficiency.

In the accompanying drawings, Figure 1 shows a central longitudinal section taken vertically through the feed-rolls and boxes, other 55 portions of the machine being shown in side elevation. Fig. 2 represents a rear elevation of the knife mechanism for feeding and guiding the blanks. Fig. 3 is a plan view of the machine. Fig. 4 is similar to Fig. 2, with the 60 upper feed-roll and pressure-plates removed and the boxes swung out of position to show their pivots. Fig. 5 is a section on line *x x* of Fig. 4. Fig. 6 shows a diagram of the upper. Fig. 7 is a detail view.

The feed-rolls *a a* are mounted in a cast-iron standard, *A*, and serve simply to move the blank, being properly grooved for that purpose. Each is journaled in a box or frame which extends across the standard from side 70 to side. The upper box is marked *B*, and it is pivoted on a stud, *b*, formed on the box near the end and working in a bearing, *c*, in the frame. The lower box, *b'*, has a like stud, and is provided with a like bearing in the other 75 side of the frame *A*. Slots 14 are cut into these studs to widen the space for the leather blanks. The boxes are pressed together by means of upper and lower springs, *d*, which have their outer bearings in the frame and 80 inner on the boxes. The boxes are separated by means of a lever, *E*, which is pivoted on the frame at 1, and is connected to the boxes by links *e e'*. The link *e* on the short end of the lever connects it with the free end of the 85 upper box, and link *e'* connects the free end of the lower box with the lever *E*, near the other end. The lever-handle when pressed down raises the upper and depresses the lower box, thus separating them, as required, when the 90 blank is to be withdrawn. In the boxes are bearings 2 for the rolls, those of the upper roll being shown clearly in Fig. 4. The shaft of one roll extends out to receive any suitable driving mechanism. The rolls are geared to each other 95 by pinions 5 on the ends opposite the crank, these pinions having teeth long enough to permit the slight separation necessary. This separation is slight and immaterial when the rolls are feeding the leather, and is without effect 100

when the rolls are opened for the retraction of the blank, as the knife is not then operating. The center of the rolls, however, always bears the same relation to the knife-edge. In front 5 of the rolls are guide-plates g g' , one pivoted at y on the upper box, the other at y' on the lower box. The construction and arrangement 10 of the plates are shown in Figs. 1 and 2. The upper plate, g , is pivoted at the pivoted end of the upper box, and the lower, g' , at the pivoted end of the lower box. They are pressed 15 toward each other by means of flat springs h h , bolted one to the upper surface of the upper and the other to the under surface of the lower box, their ends extending over the boxes and bearing on the edges of the plates. This gives 20 the plates a movement independent of the boxes and rolls, and permits them to adjust themselves to any thickness of leather, while 25 the rolls may be set near together. The inner sides of the plates are made, as shown in Fig. 1, to conform to the rolls. The pivots of the plate are set partially outside of their bearing-surfaces, to give space and proper swing, as is also the case with the boxes.

By the construction, above explained, of the boxes pivoted at opposite ends and independently-pivoted guide-plates, the plates and rolls are always centered in relation to the 30 knife-edge, the position of which is shown at K, Fig. 1, with its edges at the front of the space between the guide-plates. It is held upon a holder, S, fitted to a socket, s' , mounted on a shaft, L, turning in bearings in the 35 rear part of the frame of the machine. The axis of this shaft is in line with the center of the space between the guide-plate edges both vertically and laterally, so that as the shaft turns the central point on the edge of the knife 40 remains in line with the space. The knife-shaft has only the slight extent of rotary movement necessary to turn the edge out of the leather on the proper lines. This movement is effected by a cam-wheel, M, mounted on a 45 shaft, m, having its bearings in the lower part of the frame. A friction-wheel, n, on a stud, 6, set in the socket s' , bears on the periphery of the cam-wheel.

It will be understood by reference to the 50 patents heretofore specified that the leather blank, out of which the upper is to be made in this machine, is split from rear toward the front, through a part only in length of the leather, and that at or approximating that 55 point where the line of the front opening of the shoe unites with the line of the top of the shoe the knife is turned partly out of the leather, or if already turned out is turned still farther, so as to split only a portion or a less portion 60 thereof.

In the machine shown in my aforesaid patent the shoulder of the cut-away portion of the roll determines the line on the leather on which the knife travels after it is turned out 65 of part of the leather. The periphery of the wheel M is in part circular, the circular part commencing at the starting-point of the roller,

as shown in Fig. 1 at 15, when the machine begins its work, and extending sufficiently far around the wheel to allow that part of the blank 70 which is to be split from side to side, or to have the widest split, to pass over the knife. During this time the knife is held stationary, either in a plane parallel with the guide edges or 75 slightly inclined thereto, in order to form the rear portions of the upper thicker at the bottom and thinner at the top, and either of full width of blank or less, according to the first position of the knife, whether splitting full 80 width or less. At the proper point on the periphery of the wheel the surface begins gradually to rise, as shown at o, until it reaches a stop, 8. This high part gradually raises the roller on the stud, and as gradually turns the knife-shaft, the amount of said turning depending on the form required for the front of 85 the shoe. It is formed to turn the knife more and more out of the leather below on one side of the central line of the blank, and above on the other side of said line, the lines gradually approaching each other, as shown in the 90 diagram figure, in which the blank is represented by Q, and the lines where the knife in splitting severs the surface of the leather, as indicated at x z x z. The margins of the flaps 95 g g' are split from the leather to a thin edge, but are trimmed down after they have been split. The shaft of the cam-wheel M is provided with a gear-wheel, P, on the other side of the machine, which meshes with a gear, p, journaled in the frame, and drives a pinion, r, on one of the roll-shafts. On the same shaft with the gear p is a gear, p', driven by a worm-shaft, which is driven by a band from the loose pulley R, to which the motive power is applied. It will be apparent, however, that the 100 mechanism for driving the parts may be greatly varied.

I have shown the connections between the knife-shaft and knife as consisting of an inflexible holder, S, fitted to slide laterally in a socket, s' , and to be held therein at the proper point by a set-screw, 11. The knife is fixed to the holder by screws 12, which pass through slots in the blade, and the position of the edge 115 is adjusted by means of set-screws 13. A joint may be made in the holder, as in Fig. 7, so as to allow the knife to be turned up for sharpening. A suitable table, T, is fixed in front of the guides. The lever which opens 120 the rollers may be connected to a treadle conveniently placed.

I claim as my invention—

1. A machine for splitting blanks to form uppers, having feed-rolls, guide-plates in rear 125 of said feed-rolls, and a knife arranged in rear of the guide-plates, and mechanism, substantially as described, adapted to turn the said knife partially in relation to said guide-plates, and mechanism for imparting the required 130 motions to the parts specified, all substantially as described.

2. In a machine for splitting blanks, feed-rolls mounted in boxes, said boxes being piv-

oted at one end, the upper at one side and the lower at the other side of the frame, and yielding guide-plates placed in the described relation to the knife, all substantially as described.

5. 3. In a machine for splitting blanks, feed-rolls mounted in boxes, said boxes being pivoted at one end, the upper on one side and the lower on the other side of the frame, and yielding guide-plates pivoted at one end on the boxes and having independent movement, all substantially as described.

4. In combination, the feed-rolls, the guide-plates, and the knife mounted on a shaft and provided with a stud, and a cam-wheel adapted 15 to move the stud to turn the knife, and mechanisms, substantially as described, for operating the parts specified, all substantially as described.

5. In combination with the pivoted boxes 20 and feed-rolls mounted therein, the springs *d*, the lever *E*, and links *e*, these parts being arranged and operating in the machine substantially as described.

6. The combination, with feed-rolls and

guide-plates, and with a knife mounted on a 25 shaft adapted to turn, of a stud on said shaft, and a cam-wheel having circular and raised parts fitted to hold the knife in position during part of the operation and to turn it during a part, whereby the split portion of the 30 blank is gradually narrowed, all substantially as described.

7. In a machine for splitting blanks to form uppers of shoes, a pair of feed-rolls and guide-plates, and a splitting-knife arranged in relation to the guide-plates as described, with mechanism, substantially as described, for automatically causing the knife to incline from the plane of the guides, all substantially as described. 35

In testimony whereof I have signed my name to this specification in the presence of two subscribing witnesses. 40
